UNITED STATES PATENT OFFICE.

CHARLES P. RUTTY, OF BUFFALO, NEW YORK.

DESIGN FOR A WALL OR VENEER TIE.

SPECIFICATION forming part of Design No. 34,444, dated April 30, 1901.

Application filed March 29, 1901. Serial No. 53,560. Term of patent 14 years.

To all whom it may concern:

Be it known that I, CHARLES P. RUTTY, a citizen of the United States, residing at Buffalo, in the county of Erie and State of New York, have invented and produced a new and original Design for Wall or Veneer Ties, of which the following is a specification, reference being had to the accompanying drawing, forming a part thereof.

10 This design relates to the shape or configuration of wall or veneer ties.

The accompanying drawing represents a perspective view of a wall or veneer tie embodying my design.

15 The leading feature of my design consists of a bar or strip composed of a horizontal head portion, a horizontal point arranged at a higher level, and an upright portion connecting the head portion with the point, the head

portion being provided with a flat head, which 20 has projecting barbs or lips at its inner edges.

Referring to the drawing, A represents the horizontal head portion; B, the flat head formed at one end of the same; c, the barbs formed on the inner edges of the head; d, the 25 vertical portion extending upwardly from the opposite end of the head portion, and e is the point extending horizontally from the upper end of said vertical portion.

What I claim is—

30 The design for a wall or veneer tie, substantially as herein shown and described.

Witness my hand this 18th day of March, 1901.

CHARLES P. RUTTY.
